UNITED STATES PATENT OFFICE

JEREMIAH C. DAY, OF LEXINGTON, KENTUCKY

BUNION CORRECTOR

Application filed January 15, 1927, Serial No. 161,420. Renewed May 3, 1930.

This invention relates to improvements in devices for the correction of foot deformities and is especially designed for correcting deformities of the metatarsi, the invention being commonly known as a bunion correcting device.

An object of the present invention is the provision of a device for this purpose which may be worn upon the foot at all times, and will exert a gently pulling action upon the great toe of the wearer to pull said toe back to its normal position, and will in addition, act as an anterior support for the metatarsal joints and force the first and fifth joints into their proper positions, so that all of the joints will resume their normal positions.

Another object of the invention is the provision of novel means for constructing a device of the above character to provide for a number of pad receiving pockets, wherein one or more pads may be removably placed.

With the above and other objects in view, the invention further includes the following novel features and details of construction, to be hereinafter more fully described, illustrated in the accompanying drawings and pointed out in the appended claim.

In the drawings:

Figure 1 is a plan view looking at the top 30 of a foot with the invention applied, the dotted lines showing the abnormal position of the great toe.

Figure 2 is a bottom view of the same.

Figure 3 is a transverse sectional view of 35 the device removed from the foot, the section being taken substantially on the line 3—3 of Figure 2.

Figure 4 is a sectional view of the toe band, the section being taken substantially on the 40 line 4—4 of Figure 2.

Figure 5 is a section on the line 5—5 of Figure 2.

Figure 6 is a bottom plan view of the device spread out.

Figure 7 is a plan view of the blank from 45 which the inner member is formed.

Figure 8 is a like view of the blank which forms the outer member of the device.

Referring to the drawings in detail where- 50 in like characters of reference denote cor-

responding parts, the invention as shown comprises a foot encircling band which is indicated generally at 10, and a toe encircling band indicated generally at 11.

The foot encircling band is formed of an inner member 12 and an outer member 13, both of said members being provided with a substantially offset portion 14, by means of which a substantially central pocket 15 is provided when the members 12 and 13 are secured together. The members 12 and 13 are secured together by stitching and the sides of the central pocket 15 are indicated by stitches 16. The central pocket 15 is thus provided with a restricted mouth 17. One or more pads 18, preferably two, are adapted to be inserted in the pocket 15 and will be removably held in place by the shape of the pocket. Side pockets 19 and 20 are also provided and these pockets may receive one or more pads 21. The ends of the inner member 15 are connected by an elastic webbing 22, so that the band may be properly held in position upon the foot. The mouths of the pockets are preferably formed as indicated at 23 to facilitate the insertion and removal of the pads.

The inner member 12 is provided with an extension 24 which carries at its outer end a band 25, the latter being adapted to receive the great toe of the wearer. The extension 24 extends along the side and beneath the great toe and is so shaped that when the device is in position upon the foot, pressure upon the foot will cause a pulling action along the edge portion 26 beneath the foot, so that the great toe will be gently drawn outward to its proper position for the correction of the first metatarsal joint. The correct position of the great toe is indicated by the full lines in Figures 1 and 2, while the dotted lines of these figures indicate the abnormal position of the toe.

To assist in holding the toe in its normal position, the toe encircling band 25 is provided with a pocket 27 which carries a pad 28, this pad being positioned between the great toe and the next adjacent toe.

When in position, the pads within the pocket 15 will provide an anterior metatarsal support, so that in addition to pulling the

toe back to its normal position for the correction of the first metatarsal joint, the joints will be anteriorly supported. Also, when the device is in position, the pads within the pocket 19 will be arranged immediately at the rear of and will bear against the first metatarsal joint and will assist in forcing this joint inward as well as to provide protection for the same. Further, the pads within the pocket 20 will bear against the immediate rear of the fifth metatarsal joint for the correction of this joint, so that the device when worn, will maintain all of the metatarsi in their normal positions.

15 The invention is susceptible of various changes in its form, proportions and minor details of construction and the right is herein reserved to make such changes as properly fall within the scope of the appended claim.

20 Having described the invention what is claimed is:—

In a bunion corrector, a band adapted to encircle the foot around the metatarsal joints, and including a strip of elastic webbing to permit the band to yield when pressure is exerted upon the foot, a pad arranged centrally of the band and located beneath the foot, pads arranged at the opposite sides of the band to bear against the first and fifth metatarsal joints and to provide an anterior metatarsal support, an extension projecting forwardly from one side and the adjacent portion of the forward edge of the bottom edge of the band and arranged along the side of the foot adjacent the great toe and extending beneath the foot, a great toe encircling band carried by the extension, whereby an outward pull is exerted upon said toe when the band is extended under the pressure of the foot, and a pad carried by the toe encircling band and positioned between the great toe and next adjacent toe.

In testimony whereof I affix my signature.
JEREMIAH C. DAY.
